SOLE FOR A BOOT OR SIMILAR ARTICLE OF FOOTWEAR

Abraham Messinger, 50 Park Ave., New York, N.Y.

Filed Dec. 16, 1963, Ser. No. 77,795

Term of patent 7 years

(Cl. D7—5)

I claim:

The ornamental design for a sole for a boot or similar article of footwear, as shown.
